INTERNATIONAL STANDARD ELECTRIC CORPORATION, OF NEW YORK, N. Y.

TELEPHONE SYSTEM

Application filed May 26, 1930, Serial No. 455,636, and in Great Britain June 4, 1929.

This invention relates to semi-automatic telephone systems and more particularly to circuit arrangements associated with operators' positions whereby idle trunks available for use may be indicated to the operator.

One feature of the invention comprises circuit arrangements of the type described above, characterized in this that in response to action on the part of the operator, an indication is given individual to a trunk which has access to an idle conversational switch and which is associated with common apparatus available for use therewith.

Further features will be apparent from the description and will be set out in the appended claims.

One embodiment of the invention will be described below, but it is to be understood that the invention is not limited to the said embodiment but is capable of any variation which falls within the scope of any one of the appended claims.

The invention is described with reference to the accompanying drawings, which shows circuits at an operator's position for testing and seizing a trunk available for use. The operator has an operating key OK, a cancel key CK, a number of group marking keys such as A, B, a lamp OL and a bank of lamps LP. On pressing key OK, a switch R is caused to hunt for a trunk available for use which is determined by battery applied to a test conductor such as BPT over the circuit shown, the contacts above the broken line being individual to a trunk and its conversational switch while those below the said line are individual to a common bye-pass circuit, associated with the said trunk. When an available trunk is found the switch is stopped, lamp OL lights and tens and units lamps in the bank LP are lighted to indicate the said trunk. The test conductor H of the trunk is earthed to mark the trunk in the banks of a bye-pass switch R1 and when, after the bye-pass has been set by the dialled digit or digits,

the said bye-pass switch has found the trunk, a holding circuit over the conductor BPT is removed and the lamps release. By throwing one of the group keys, such as A or B in conjunction with key OK, a trunk having outlets in a wanted direction is found. If an indicated trunk is found to be faulty, the switch R can be stepped therefrom by pressing key CK.

The circuits will now be described in detail.

When an operator requires to find a free trunk associated with a free bye-pass circuit the key OK will be operated closing the circuit over the magnet R through its interrupter springs contacts pp1, hh2 to ground at the key OK. The switch rotates and tests from ground at the key OK from the winding of relay PP and one wiper T of the switch to the bye-pass test conductor BPT and searches for a battery potential. When the switch reaches a contact on which there is battery potential, the relay PP will operate opening the circuit of the magnet R. The battery potential will signify the freedom of a conversational switch and a bye-pass circuit, the battery being applied over wiper K of the switch R2, home contact and wiper 8 of switch R1, tb6, e7, wiper 6 and home contact of the switch R1, tb1, gs1, bs1, bye-pass test conductor BPT, wiper T, winding of the relay PP to ground at the key OK. The functions of the contacts in this circuit will be discussed later to show how the circuit would be opened at any time while either the trunk and its switching device from the bye-pass associated therewith is in use. The portion of relay PP closes the circuit for the relay HH from battery through the winding of HH, key CK, pp1, hh2 to ground at the key OK. Relay HH closes its light contact hh1 thereby making itself independent of the relay PP. Earth is extended from key OK via hh1, key CK, hh3 to wiper T and relay PP is short circuited. The contact hh2 opens the driving circuit of the magnet R.

to prevent any further steps being taken when the relay PP releases. The lamp OL will be lighted in multiple with the relay HH and acts as a supervisory signal to the operator. Contacts $hh5$ and $hh6$ extend the multiple jack associated with the outlet to the bye-pass positive and negative conductors. Contacts $hh7$ and $hh8$ extend the ground potential to a lamp panel LP thereby indicating by the combination of lamps lighted the outlet number which has been taken into use. This discrimination may be given by two Lamp strips, one of which will represent tens and the second units. Bank contacts associated with the contact $hh7$ will be wired in sets of 10, whereas the bank contacts associated with the contacts $hh8$ will have every tenth contact multiple together. The operator will insert the calling plug in the multiple jack OJ, which as has already been explained is extended direct to the bye-pass circuit and as a result dialling may commence immediately.

A relay TB in the bye-pass circuit is operated immediately the circuit is seized, removing the battery potential from BPT and substituting earth potential to hold the relay HH and the operator may now restore key OK.

Contact $hh4$ extends ground to the test conductor H of the conversational path and is required to enable the bye-pass switch R1 to find trunk in use. When the bye-pass circuit is impulsed switch R1 responds and switch R2 chases so that the test circuit is further opened at wipers 6, 8 and K. The switch R1 then hunts in the second part of its banks for the trunk marked by ground on conductor H, and when it is found the above mentioned relay TB releases, so that ground is removed at $tb1$. Relay HH and the lamps OL, LP are therefore released. When the conversational switch of the trunk has found the outlet marked by the switch R2, a relay GS in the conversational trunk circuit is operated so that contact $gs1$ in the test circuit is opened. When the wanted line is found and tests free the relay GS is released but a relay BS immediately operates, re-operating GS, which locks up, and both contacts $gs1$, $bs1$ are opened. The bye-pass circuit is then released and the switches home so that test potential is placed over $tb1$ and the $gs1$, $bs1$ contacts of idle trunks in the group which are now made available for use. Relay GS will remain operated until both subscribers have hung up.

In certain cases the operator may require a trunk in a particular group and this discrimination is effected by means of keys such as A and B which are used with the following modification to the wiring; the connection marked X on the key OK is removed and the dotted connection from the key to wiper C is wired. The modification makes the testing

circuit not only dependent upon the operation of the key OK, and also on the position of the wiper C. The bank contacts searched over by the wiper C are arranged in groups corresponding to the group of the outlets. All the bank contacts of each group being multiplied together and connected to a key such as A or B. By operating the key A for instance simultaneously with the OK key, the operator will cause the trunk indicator switch to test only over the outlets of the described group.

If an indicated trunk is found to be faulty the switch can be stepped therefrom by throwing a cancel key CK. This operation puts full earth on the switch magnet R so that when the key is restored, the switch will take a step forward. It will be appreciated that the key OK might be combined with the keys such as A, B, so that the operator would only have to throw a single key to obtain an indication of an available trunk in a particular direction.

What is claimed is:—

1. A telephone system comprising an operator's position, outgoing trunks terminating therein, conversational switches individual to said trunks, control apparatus associated in common with a plurality of said trunks and means adapted to identify an idle trunk in response to potential applied over a circuit including normal contacts both of a free conversation switch and of a free control apparatus.

2. A telephone system comprising an operator's position, outgoing trunks terminating therein, conversation switches individual to said trunks, control apparatus associated in common with a plurality of said trunks, a hunting switch, means adapted to be actuated by the operator to cause said hunting switch to hunt for an idle trunk which has access to an idle conversation switch and which is associated with an idle control apparatus and means adapted to be operated automatically in the event said idle trunk is faulty to step the hunting switch forward on to another trunk.

3. A telephone system according to claim 2 wherein said means which is adapted to step the hunting switch forward upon being operated closes the circuit of the hunting switch and upon being released opens said circuit.

4. A telephone system comprising an operator's position, outgoing trunks terminating therein, conversational switches individual to said trunks, bye-path circuits associated in common with a plurality of said trunks and means adapted to be actuated by the operator to identify one of said trunks accessible to an idle switch and associated with an idle bye-path circuit.

5. A telephone system, comprising an operator's position, outgoing trunks terminating therein, conversation switches individual

to said trunks, bye-path circuits associated in common with a plurality of said trunks, a hunting switch, means adapted to be actuated by the operator to cause said hunting switch 5 to hunt for an idle trunk which has access to an idle conversation switch and which is associated with an idle control apparatus, and means whereby an impulsing circuit is formed between the outgoing end of the selected 10 trunk and the leads to the bye-path circuit over the said switch.

6. In a semi-automatic telephone system comprising a single control circuit associated in common with a group of conversational 15 switches, adapted to control the setting up of connections over any one of the latter in the case of circuit arrangements associated with an operator's position at which an indication individual to an idle trunk available for use by the operator may be given, and means whereby in response to an action on the part 20 of the operator an indication is given of a trunk individual to an idle conversational switch and an idle control circuit associated 25 with the latter.

7. In a semi-automatic telephone system, the combination of a group of switches individual to a switching stage and each associated and adapted to be controlled by a common 30 control circuit individual to the said stage, and means responsive to an action on the part of an operator whereby a free switch associated with a free control circuit is indicated to the operator.

35 8. A telephone system comprising an operator's position, outgoing trunks terminating therein, a group of switches individual to said trunks, common control circuits associated with a plurality of said trunks, and means adapted to be actuated by the operator 40 to identify one of said switches which is free and is associated with an idle control circuit.

45 9. A telephone system comprising an operator's position, outgoing trunks terminating therein, conversation switches individual to said trunks, control apparatus associated in common with a plurality of said trunks, a hunting switch, means adapted to be actuated by the operator to cause said hunting 50 switch to hunt for an idle trunk which has access to an idle conversation switch and which is associated with an idle control apparatus, and means adapted to identify an idle trunk in response to potential applied 55 over a circuit including normal contacts both of a free conversation switch and of a free control apparatus.

60 10. A telephone system comprising an operator's position, a hunting switch, a plurality of groups terminating at said position and in said switch, conversational switches individual to said trunks, control apparatus associated in common with a plurality of said trunks, means adapted to be actuated by the operator to identify one of said plurality of

groups of trunks and to cause said hunting switch to hunt in said group for an idle trunk which has access to an idle conversation switch and which is associated with an idle control apparatus and means adapted to identify 70 said idle trunk in response to potential applied over a circuit including normal contacts both of a free conversation switch and of a free control apparatus.

In witness whereof, I hereunto subscribe 75 my name.

ESMOND PHILIP GOODWIN WRIGHT.
